(57) **CLAIM**

We claim the ornamental design for a tag for attaching a location tracker to a belonging, as shown and described.

DESCRIPTION

FIG. 1 shows an isometric view of a tag for attaching a location tracker to a belonging, showing our new design.

FIG. 2 shows a front view thereof;

FIG. 3 shows a back view thereof;

FIG. 4 shows a left side view thereof;

FIG. 5 shows a right side view thereof;

FIG. 6 shows a plan view thereof;

FIG. 7 shows a bottom view thereof; and,

FIG. 8 shows another isometric view thereof.

The broken line portion of the figure drawings is included to show portions of the article that form no part of the claimed design. The article is shown with a symbolic break in its length. The appearance of any portion of the article between the break lines forms no part of the claimed design.
